UNITED STATES PATENT OFFICE.

ROBERT M. FRYER, OF NEW YORK, N. Y., ASSIGNOR TO FRANK B. COLMAN, OF PASSAIC, NEW JERSEY.

INTERNAL-COMBUSTION ENGINE.

1,128,125.

Specification of Letters Patent.

Patented Feb. 9, 1915.

Application filed March 4, 1910. Serial No. 547,302.

To all whom it may concern:

Be it known that I, ROBERT M. FRYER, a citizen of the United States, residing in the city, county, and State of New York, have 5 invented certain new and useful Improvements in Internal-Combustion Engines in which a reciprocating piston is actuated in one direction by combustion of an explosive mixture and in the opposite direction by 10 steam generated within the cylinder by direct application to a charge of vaporizable fluid of the heat arising from the explosion.

An object of the invention is to utilize 15 the heat resulting from the explosion on one side of the piston to generate steam on the opposite side, thus to avoid the use of a separate steam generating furnace or apparatus.

20 A further object is to secure certainty of action and avoid stoppage of the engine, and to this end I provide a plurality of igniting means so that in case if one fails to operate ignition may be effected by another.

A further object is to provide an engine 25 in which alternate charges are exploded in separate and independent combustion chambers, so that if one charge fails to explode 30 the other may ignite to keep the engine in action and thus also prevent stoppage.

A further object is to utilize the water 35 employed for steam generation as a cooling and lubricating medium and as a preventive of leakage past the piston.

A further object is to so construct and 40 arrange the parts of the engine as to practically eliminate liability of derangement and to avoid loss of time and labor incident 45 to repairs and readjustment. And a final object is to provide an efficient and reliable engine which, by reason of its compactness and lightness, shall be admirably adapted for use on flying machines operated by motive power.

With the above and other objects in view, as will appear as the nature of the invention is more fully set forth, the same consists of a cylinder, a reciprocating piston 50 therein, a plurality of combustion chambers on one side of the piston, means for supplying explosive charges thereto alternately, means for igniting said charges, valved passages through the piston for admission of 55 the products of explosion to the opposite

end of the cylinder and means for introducing charges of water into the cylinder on the side of the piston opposite the combustion chambers, all as will be herein described in detail.

In the accompanying drawings illustrating my invention: Figure 1, is a central vertical section. Figs. 2, 3, 4, 5 and 6 are detail views fully described hereinafter. Fig. 7 is a horizontal section on the line 60 7-7, Fig. 1. Fig. 8 is a similar section on line 8-8. Fig. 9 is a perspective view of one of the annular check valves shown in section in Fig. 1. Fig. 10 is a plan view of one of the valve seats. Fig. 11 is a plan view 65 of the exhaust valve and the spider for controlling the same. Fig. 12 is a plan view of the spider which controls the valves shown in Figs. 9 and 10, and Fig. 13 is a plan view of a rotatable spider frame which 70 is located in the top of the cylinder and which opens the valves of the piston to permit the heated products of the exploded charges to pass to the steam chamber above 75 the piston.

Referring to the drawings:—A designates the cylinder and B the reciprocating piston working therein. The piston is preferably formed in two parts or plates, as shown in Fig. 1, the lower part having in 80 its upper face two annular and concentric valve chambers N and N' and openings or passages P P' leading into the respective chambers wherein valves O O' are located. The head 5 of the cylinder comprises two 85 plates, as shown, the lower one of which has an annular valve chamber S in communication with the interior of the cylinder through passages U. A valve T in the valve chamber has its seat against the 90 upper plate and controls exhaust passages therethrough for the escape of the steam and products of combustion at the completion of the down-stroke of the piston. On the upper side of the head 5 is also a central chamber 4 which is supplied, from any 95 suitable source, with water for steam generating purposes, the water being introduced into the cylinder, above the piston in regulated charges as will be explained presently.

Below the cylinder A is a second cylinder K and within the latter is a cylinder K', the two forming between them an annular chamber J, opening at the top into the cylinder A.

Connected with the piston B and forming practically a part thereof is a depending annular chamber F having at the top thereof outlet passages or openings G H, controlled by annular valves G' H', and at the bottom inlet passages F' controlled by an annular valve seated in a valve chamber 1.

Within the cylinder K' and spaced apart therefrom is a central cylinder 40 which forms a carbureter; it has openings at the top controlled by an annular check valve 42. Passages 43 in the walls of the cylinder open into the chamber 40 at the top, these passages being for the purpose of conveying hydro-carbon into the carbureter from a suitable source of supply (not shown) which is to be connected at the bottom. It may be stated here that the source of supply should be sufficiently elevated so that the hydro-carbon will be supplied to the carbureter by gravity. The carbureting chamber is partially filled with porous or absorbent bodies 44, preferably spherical although the shape is immaterial, which absorb and take up the hydro-carbon as it is delivered through the passages 43, these bodies having for their purpose to aid or promote volatilization of the hydro-carbon and thus facilitate carburization of air drawn in through valved inlets 41 as hereinafter described.

The piston rod W, which extends centrally through the carbureter, is bored from the top to form therein a water chamber 6 which is supplied with water from the chamber or reservoir 4 through a pipe V which extends through the cylinder head and is capable of reciprocatory movement. This pipe carries at its upper end, above the cylinder head, the spider X—Fig. 11—which is connected with stems U' of annular valve T. The chamber 6 in the piston rod is of such depth, and the pipe V is of such length, that as the piston approaches the limit of its upward stroke a tappet V' in the bottom of chamber 6 will strike the end of pipe V and lift the same and the spider X carried thereby, and so seat the valve T and close the exhaust passages in the cylinder head 5. Near its lower end the pipe V has a fixed collar 16, so located that as the piston approaches the limit of its downward stroke the spider Z—Fig. 2 will strike the collar and pull the pipe and the spider X downward, unseating the valve T and opening the exhaust passages.

At the lower end of the pipe V is a head 6'' which snugly fits the chamber 6, and which may be denominated a pump piston, its office being to pump water from the chamber 6 into the cylinder A above the piston B. The head 6'' has passages 6''' therethrough controlled by a check valve 6''. When piston B moves upward water is forced through the passages 6''' and on the

downward stroke the water so forced through is retained by the check valve and is forced out at the top under the spider Z, which spreads it in a thin sheet over the top of the piston.

The spider Y carries two annular series of bosses 14, 15 those of one series being disposed in staggered relation to those of the other series, as shown in Fig. 13. These bosses stand in the paths of movement of heads Q', Q'', of valve stems O'', O''' of the annular valves O, O', and when struck by said heads unseat the valves and open the passages controlled thereby to permit the heat and products of the charges exploded in the combustion chamber D E, to pass through the piston to the upper side thereof. Each of the valves O O' has six stems at an annular distance of sixty degrees apart (see Figs. 7 and 8) to avoid tilting of the valves, and the stems of the two valves are in the same radial lines. The spider Y is mounted in the top of the cylinder A adjacent to the head 5, on a rotatable sleeve 12, extending through the head, the sleeve and spider being rotated step-by-step through angular distances of thirty degrees at each step to bring first one series of bosses, and then the other, into position to operate the respective valves, O, O' in the manner described.

The means for rotating the sleeve 12 and spider Y comprises a bevel gear 11 at the top of the sleeve, a bevel gear 10 mounted at the side of the sleeve and intermeshing with gear 11, a ratchet wheel 8 fixed with relation to gear 10 and having twelve teeth, a lever 7 mounted on the axis of the gear and ratchet and carrying at one end a pawl 7 the other end being connected to the spider X by a short rod or link 9 all as shown in Figs. 1, 2 and 3. As the pipe is moved up and down by the tappet V' and the spider Z, as already explained, the rod 9 is reciprocated, operating the lever 7 and its pawl, rotating the ratchet wheel, and with it the bevel gear 10, and this being in gear with gear 11 it follows that each reciprocation of piston B effects a rotary movement of thirty degrees of sleeve 12 and spider Y, whereby first one series of bosses 14 or 15 and then the other is positioned to be struck by valve stem heads Q', Q'', so that the valves O, O' are alternately unseated, the purpose of which will appear presently.

On the upper side of piston B are annular check valves R, R' through which the stems O'', O''' of the valves O, O', loosely pass. These valves R, R' also control passages through the piston B, which passages may, or may not, be the same as those controlled by the valves O, O'. The valves R, R, close by steam pressure in the upper part of the cylinder to prevent

passage of steam during the down stroke, but at the completion of said stroke the exhaust valve T is opened, and the steam charge escapes, whereupon the pressure of 5 the residual steam and products of combustion, which are compressed on the down stroke, lift the valves and escape to make room for an explosive charge. This is a most important feature in the operation 10 of the engine, as will presently be seen.

D, E, are the explosion chambers, one within the other, in which the explosive charges are exploded first in one and then in the other. These two chambers are of 15 substantially equal capacity, and the capacity of the two together is substantially equal to that of chamber J. The combustion chambers D, E, are each provided with a plurality of electric sparkers or igniters, 20 each comprising a spear-shaped head 48 surmounting a rod carried by a tube or casing 49 vertically adjustable in the base of the chamber and a pair of spaced contact jaws 47 carried by the piston on its under side. 25 The said jaws have enlargements at their ends so spaced that they will both contact with the head as they pass the same. The jaws 47 are of such length that contact with the heads 48 is made just before the piston 30 reaches the limit of its stroke, and is broken as the limit is reached, thus producing a spark or sparks. The heads 48 will then stand between the jaws 47, out of contact therewith, as will be readily understood 35 from Fig. 1; then as the up-stroke begins contact will again be made and broken, again producing a spark or sparks. It will now be seen that by providing a plurality 40 of sparkers (five are indicated in the outer chamber in Fig. 7) each of which operates at least twice at each stroke, the chances of ignition are many times multiplied and failure is practically impossible so long as the electrical connections remains intact. 45 The piston is packed as usual, the packing shown being of the ordinary three-ring variety for which nothing is claimed. Two outside expansible rings C are backed by an inner expansible ring which covers both 50 the outer rings, and the inner ring is in turn backed by expanding coiled springs A². The spring action of the packing may be supplemented by pressure applied through passages N² extending from valve 55 chamber N'. The chamber F is provided at its lower end with inner and outer packing of similar character to prevent leakage of gas from chamber J.

The structural features of the engine having now been described a description of the 60 operation will be given, as follows:—Hydro-carbon having been introduced into the carbureting chamber 40 through the inlet passages 43, and water supplied to the chamber 65 or reservoir 4, from suitable sources of sup-

ply, as described, the engine is ready to be started, this being effected by imparting to the piston (either by manual or mechanical power) one or two reciprocations, (one will usually be sufficient) during which the 70 chamber F, which I will now call the receiver, acting by suction will on the up-stroke draw from the carbureter, past the check valve 42 and through the passages J' into the chamber J, an explosive charge 75 comprising a mixture of volatilized hydro-carbon and air drawn in through the inlets 41 as already explained. On the return or down-stroke of the piston the explosive mixture drawn into the chamber J on the up-stroke will be compressed into the receiver 80 F and near the completion of the stroke will pass into one or the other of the explosion chambers D, E, and will be exploded therein when the sparkers 47—48 contact as 85 above explained, whereupon the piston is driven upward. The engine is now in operation. Supposing now the piston B to be on the up-stroke (Fig. 1) as a result of an explosion in chamber E, the valve O' being 90 closed, when the stroke is practically completed the heads Q'' of the valve stems O'' will strike the bosses 15 of spider Y, the valve will be unseated, the heat and products of the exploded charge will pass 95 through the piston to the upper side thereof, the tappet V' will strike the end of pipe V and lift the same and force a charge of water under the spider into the hot gases and products of explosion, the water will 100 be converted into steam, the pressure of which will seat the check valves R, R', and drive the piston down. Also, during the up-stroke of the piston a charge of explosive mixture is drawn from the carbureter 40 into the chamber J, the exhaust valve T is closed by the lifting of the pipe V and spider X, the ratchet lever 7' is vibrated and the pawl 7 carried into engagement 105 with the next tooth of ratchet wheel 8 preparatory to a movement of spider Y to bring the bosses 14 thereof into operative position when the spider Z strikes the collar 16 on pipe V on the down-stroke. Now, 110 during the down-stroke (the valve O' being still open) the explosive mixture in chamber J, held against back flow by the check valve 42, is compressed into the receiving chamber F, and since the chamber J, is much larger than the chamber F (by preference, at least three times as large) the volume of the mixture compressed into chamber F is much reduced and the pressure correspondingly increased. Now it is to be noted that 115 on the previous up-stroke the pressure of the driving charge in chamber E held the valve G' closed, and that there being at such time no pressure on the valve H' the latter was lifted by the pressure in chamber F and a charge for the next up-stroke expanded 120 125 130

into the chamber D, such charge being compressed during the down-stroke and ignited at the completion thereof, and now, on the resulting up-stroke the operation is reversed: 5 the pressure in chamber D holds the valve H' to its seat, the mixture compressed into the chamber F on the last down-stroke lifts the valve G' and expands into chamber E to be compressed and ignited on the down- 10 stroke, as before. It is to be noted that whichever of the valves O or O' is opened on the up-stroke is closed by the lifting of spider Z at, or near, the completion of the down-stroke, and that both valves (O, and 15 O') are closed at the beginning of the up-stroke, so that there may be no escape of explosive mixture. It will of course be understood that the cylinder, after a few explosions, becomes highly heated and that in 20 consequence the water in the chamber or reservoir 4, from which the engine is supplied, will also be heated and that its conversion into steam will thereby be greatly facilitated.

25 What I claim as my invention and desire to secure by Letters Patent of the United States is—

1. A combined internal combustion and steam engine, comprising a cylinder, a piston 30 ton therein, means for introducing an explosive or combustible mixture on one side of the piston, means for introducing a steam producing liquid or fluid on the other side of the piston, the said piston having a 35 valve-controlled passage therethrough for the passage of the products of combustion or explosion from one side to the other.

2. In an internal combustion engine, a cylinder, a cylindrical piston having an annular projection on the outer side, under 40 which an explosion chamber is located, forming a combustion chamber therein, means for introducing an explosive or combustible mixture thereto, means for introducing a steam producing liquid into the cylinder on the other side of the piston, the said piston having a valve-controlled passage therethrough for the passage of the products of combustion or explosion from 45 one side to the other.

3. An internal combustion engine comprising a cylinder embracing combined explosion and steam generating chambers, a piston separating the said chambers, means 55 for supplying an explosive charge to the explosion chamber, means for directing the exploded charge, or products of combustion, to the steam generating chamber and means for supplying water to the latter 60 chamber.

4. An internal combustion engine comprising a plurality of independently operable explosion chambers, one within the other, a flash steam generating chamber, a 65 piston, the head of which separates the said

combustion chambers from the steam generating chamber, the body of the piston constituting one of the explosion chambers, means for establishing alternate communication between the respective explosion 70 chambers and the steam generating chamber, and means for supplying water to the latter chamber.

5. An internal combustion engine comprising a plurality of independently operable explosion chambers, one within the other, a flash steam generating chamber, a piston between the combustion and steam generating chambers and constituting one of the combustion chambers, means for establishing alternate communication between the respective explosion chambers and the steam generating chamber, and means actuated by the piston for supplying water to 80 the latter chamber.

6. In an internal combustion engine, a cylinder divided into a plurality of chambers, one of which constitutes a steam generating chamber and the others explosion chambers, piston separating the two series 90 of chambers, means for supplying an explosive mixture to the explosion chambers, means for directing the exploded charge to the steam generating chamber, the upper surface of the piston constituting a water 95 evaporator.

7. In an internal combustion engine, an inverted, or open-bottomed cylindrical piston, in conjunction with an inner and an outer cylinder disposed beneath a cylinder 100 within which the said cylindrical piston operates, the arrangement providing beneath the said piston head a plurality of explosion or combustion chambers through the division of the surface below the piston 105 head, so as to constitute an annular and a central combustion chamber, by the cylindrical portion of the piston, annularly situated between the said combustion chambers, as shown.

8. In an internal combustion engine, a cylinder, a second cylinder disposed concentric thereto, a cylindrical piston with head of greater diameter, providing a plurality of combustion chambers underneath 115 the same, one inside and the other outside of the said cylindrical piston working between the said cylinders, and means for supplying carbureted air to the combustion chambers.

9. In an internal combustion engine, a cylinder, a second cylinder disposed concentric thereto and providing a plurality of combustion chambers through means of a cylindrical piston working between the said cylinders, and means for supplying carbureted air to the combustion chambers.

10. In an internal combustion engine, a cylinder, an open-bottom cylindrical piston with inlet valve therein provided, with an

interior combustion chamber, an annular combustion chamber surrounding the same, through means of a pneumatic chamber in the said cylindrical piston spacing the two 5 aforesaid combustion chambers.

11. In an internal combustion engine, a cylinder, a hollow cylindrical piston composed of two parallel annular walls, joined at the top and bottom by valve-seated heads 10 therein, constituting a pneumatic pump-plunger, working in an annular space below the piston head between two corresponding annular walls, whereby this annular pump-plunger, or cylindrical portion of the piston, during its up-stroke, fills the annular space wherein it reciprocates, with gas, and upon its down-stroke, forces this gas into the hollow space of the said annular plunger, from whence it is delivered alternately, to 15 the combustion chambers, one inside and the other outside of the cylindrical piston, below the head thereof, and means to receive, and to deliver under pressure the desired gaseous bodies therein employed, through 20 the action or reciprocation of the said piston wherein valve chambers and corresponding valves, for the conduction and regulation of the gases from combustion chambers are located, as shown.

30 12. In an internal combustion engine, a cylinder, the upper portion of which constitutes the steam generating chamber and the lower portion a combustion chamber, a piston in the said cylinder in the head of 35 which piston, valves and corresponding valve chambers are arranged, the piston being provided with communicating openings between the combustion and steam generating chambers.

40 13. In an internal combustion engine, a cylinder embodying a steam generating chamber and a combustion chamber, a piston dividing the said chambers, a valve or valves in the said piston for controlling communication between the combustion and steam generating chambers, and means for seating the valves comprising a spider frame through the arms of which the valve stems project, which valve stems are provided with 45 bosses at the top to be engaged by arms of the spider frame, and a rod provided with a collar to engage with the under side of the said spider frame to hold the latter at rest during a period of the downward stroke of 50 the piston, thus to seat the valves.

55 14. In an internal combustion engine, a cylinder constituting a steam generating chamber and a combustion chamber, an open-bottom cylindrical piston, producing 60 a plurality of explosion chambers below the head thereof, valves for controlling communication between the combustion and steam generating chambers, means for seating the valves comprising a spider frame supported on the piston and through which

the stems of the valves project, the latter being provided with bosses or lugs, to be engaged by the spider frame, a rod provided with a collar to engage with the under side of the spider frame to hold the latter at 65 rest during a period in the descent of the piston, thus to seat the valves, and means for alternately opening the valves comprising a spider frame arranged beneath the cylinder head and provided with two series of downward extending bosses arranged alternately to engage with the lugs or bosses of the valve stems, and means to impart a step by step motion to the last named spider frame, whereby, each alternate stroke of the 70 piston will cause the same valve to be opened.

75 15. In an internal combustion engine, a cylinder embodying a flash steam generating chamber and a combustion chamber, an inverted or open-bottom cylindrical piston, embodying a plurality of explosion chambers, valves in the piston for controlling passage between the combustion and steam generating chambers, a spider frame disposed above the piston and through which the stems of the valves project, the latter being provided with bosses to be engaged by the spider frame, a piston rod provided with a well, means for supplying water to the 80 well comprising a hollow rod communicating with a source of water supply, a ported piston carried by the lower portion of the rod and operating in the well, a by-pass valve loose on the rod and normally closing 85 the piston ports, and means for retarding movement of the spider frame on the downward stroke of the piston to seat the main piston valve comprising a collar rigid with the rod with which the under side of spider 90 frame contacts.

95 16. In an internal combustion engine, a cylinder embodying a steam generating and a combustion chamber, an inverted or open-bottom cylindrical piston, below the head of 100 which a plurality of explosion chambers are located, one being inside of the said piston, valves carried by the piston for controlling communication between the combustion and steam generating chambers, stems carried by the valves, a spider frame supported by the piston and through which the stems project, lugs or bosses carried by the upper 105 ends of the valve stems to retain them in operative connection with the arms of the spider frame, a piston rod provided with a well the open end of which is covered by the spider frame, means for supplying water to the well comprising a hollow rod the

110 upper end of which communicates with a source of water supply and the lower end of which projects into the well, a ported piston carried by the lower portion of the rod, a by-pass valve loose on the rod and normally closing the ports of the last named 115 120 125 130

- 6
- 5 piston, whereby on the upward stroke of the main piston, water is forced above the bypass valve and on its downward stroke the water is caused to lift the spider frame sufficiently to permit a thin sheet of water to be discharged laterally within the steam generating chamber where it is met by the highly heated products of combustion and flashed into steam, and means for retarding
10 the movement of the spider frame on the downward stroke of the main piston to seat the valve carried thereby, comprising a collar rigid with the hollow rod and with which the center of spider frame contacts.
15 17. In an internal combustion engine, a cylinder the upper part of which constitutes a steam generating chamber and the lower portion, below the piston head, answers for a combustion or explosion chamber, a second cylinder forming a base for the first, a third cylinder within the second concentric therewith, an annular space between the latter named cylinders constituting a pneumatic pump chamber, a fourth cylinder located within the third and constituting the carbureting chamber provided with an annular check valve, open-bottom cylindrical piston with annular chamber within and with valves opening thereto and therefrom
20 25 30 while acting as an annular pump plunger in said annular space between the second and third cylinders, communication being

had through the wall of the third cylinder and passage surrounding the carbureter with annular valve thereon, means for admitting 35 air to the carbureter from below and for supplying hydrocarbonaceous liquid fuel to the carbureter from or near the top and means within the carbureter to effect progressive and rapid evaporation of such fuel 40 from heavier to lighter, drawing the gases in, through and from the carbureter by the action of the piston and in turn forcing the same within the storage chamber and delivering them therefrom, through valves 45 thereon provided, to the combustion chambers as shown and described.

18. In an internal combustion engine comprising a plurality of independently operable combustion chambers, a steam generating chamber, a piston constituting one of the combustion chambers, means for establishing alternate communication between the combustion and the steam generating chambers, independently operable sparkers 50 or igniters in the combustion chambers, and means for supplying water to the steam generating chamber in regulated impulses.

In testimony whereof, I hereunto set my hand, in presence of two witnesses.
